UNITED STATES PATENT OFFICE.

PATSY CARRIGAN, OF BLOOMINGTON, ILLINOIS.

RAIL CONNECTOR AND BRACE.

1,121,162.

Specification of Letters Patent. Patented Dec. 15, 1914.

Application filed March 16, 1914. Serial No. 825,032.

To all whom it may concern:

Be it known that I, PATSY CARRIGAN, a citizen of the United States, residing at Bloomington, in the county of McLean and State of Illinois, have invented certain new and useful Improvements in Rail Connectors and Braces, of which the following is a specification.

This invention relates to rail connectors and braces, and, while primarily designed for connecting and bracing railway rails, may also be employed for adjustably connecting and bracing other rails, bars or structural elements.

The primary object of the invention is to provide a coupling connection whereby rails or like elements may be held firmly in their correct relative positions against spreading, and whereby adjustment is afforded to maintain the rails or connected elements in proper position and to permit of their relative adjustment in a ready and convenient manner when occasion requires.

A further object of the invention is to provide a coupling connection and brace which is composed of a pair of main sections adjustably connected together, each main section in turn being adjustably and detachably connected, whereby either main section may be adjusted independently of the other and also independently connected with or disconnected from the rail or other element to be braced, rendering the device of particular service and value in railway track repair and construction work.

The invention consists of the features of construction, combination and arrangement of parts, hereinafter fully described and claimed, reference being had to the accompanying drawing, in which:

Figure 1 is a side elevation of a rail connector and brace constructed in accordance with my invention; Fig. 2 is a top plan view of the same; and Fig. 3 is a vertical longitudinal section through a portion of the device.

In carrying my invention into practice, I provide a connector and brace comprising duplicate members 1 and 2, each consisting of a plurality of sections terminating at their inner or adjacent ends in rods 3 which are threaded for the reception of a turn buckle 4, whereby the connector and brace as a whole may be adjusted as to length and the two members held securely connected. Lock nuts 5 are provided to engage the rods

3 and abut against the ends of the turn buckle 4 to hold the latter from casual retrograde movement, thus insuring a safe and reliable connection.

Each member 1 and 2 is composed of a pair of sections 6 and 7, the section 7 being preferably integral with the rod 3, as shown, while the section 6 carries at its outer end a clip 8 of suitable form to receive and engage the base of the rail. The clips 8 of the two members 1 and 2 are adapted when applied to the rails of a track, or to other structural elements, to hold the same firmly united and to sustain them against lateral pressures, thus effectually bracing the rails or structural parts against spreading or relative displacement.

In practice, the clip 8 may be formed independently of the section 6, and said plate 7 and section 6 may be formed with lapping plates 9 and 10 respectively, which are riveted, welded or otherwise firmly united. The sections 6 and 7 are adjustably connected together and for this purpose are provided with lapping plates 11 and 12 formed with terminal abutment shoulders 13 and 14 whereby their relative inward movement for shortening the length of the coupling member is limited. The meeting faces of these plates 11 and 12 are provided with engaging teeth 15, by which when the plates are held assembled they are locked firmly against relative movement. The plates are formed with longitudinal slots 16, 90 through which pass a fastening bolt 17 provided with a clamping nut 18 arranged to bear against a washer 19, the washer being clamped by the nut against one of the plates, while the head of the bolt is clamped against the other plate, thus maintaining the teeth of the plates in interlocking engagement. By removing or slackening the nut to a sufficient extent to permit the toothed faces of the plates to separate, it is evident that said plates may be adjusted longitudinally on each other to vary the length of the coupling member, and that after adjustment has been made the nut may be tightened to lock the plates again securely together.

My invention is especially designed for connecting the rails of railway tracks, to hold the rails braced firmly against spreading or moving out of their proper relative positions under the stresses and strains to which they are subjected. It will be observed that the adjustable connection between the members 1

and 2, as well as the adjustable connections between the sections of each member, permit the brace to be adjusted to a wide degree to suit the distance between the rails, 5 while permitting any slack or looseness to be taken up by simply adjusting the turn buckle, so that the proper distance between the rails can be maintained. Where the adjustment afforded by the turn buckle is not sufficient, the adjustable connections between the sections of each member 1 and 2 10 permit of a further range of adjustment, and it will be observed that these sections of each member are also detachably connected, allowing either rail to be shifted or removed without disturbing the other, and of the removed rails being replaced without disturbing the ties or other rail, a feature of construction and use which is an important factor in railway repair work. It 15 will be evident that in removing either rail, the member engaging the particular rail in question may be disconnected therefrom by unscrewing said member at the turn buckle connection or disconnecting the outer section of the member from the inner section thereof by removal of the bolt 17, the convenience of which may be manifest. The 20

invention will also be found useful and advantageous in connecting other rails or bars 30 or structural elements to hold the same braced and against relative movement, while permitting adjustments, repairs and removals to be made with ease and facility.

Having thus described my invention, I 35 claim:

A connector and brace comprising duplicate members, each having a threaded rod at its inner end and a rail-engaging clip at its outer end, each of said members consisting of a pair of sections carrying the rod and engaging member, respectively, said sections being provided with longitudinally slotted toothed interlocking plates, bolts 40 passing through the slots in said plates and adapted to hold the toothed faces thereof interlocked, and a turn buckle uniting the threaded rods at the inner ends of the duplicate members.

In testimony whereof I affix my signature 50 in presence of two witnesses:

PATSY CARRIGAN.
